ELASTIC CORSET, GIRDLE, AND SIMILAR WEARING APPAREL FOR WOMEN

Heinrich Hölscher, Heubach, Wurttemberg, Germany, assignor to Triumph Bekleidungs u. Textilwerke G. m. b. H., Heubach, Wurttemberg, Germany

Application September 14, 1953, Serial No. 380,943

1 Claim. (Cl. 2—36)

This invention relates to an elastic hip-shaping article, such as a corset or girdle, provided with a front panel made, for instance, of satin, and having stiffening members incorporated into the same.

Many suggestions have been made with regard to these stiffening members which may consist of flat vertically or horizontally arranged metal strips, or of spiral springs.

Moreover, U-shaped stiffeners have been applied to the resilient stomach covering portions of the corsets or girdles; the two shanks of these U-shaped stiffeners extend substantially parallel to each other. The end portions of these stiffener shanks, however, exert a pressure onto the body of the wearer and this is particularly noticeable when the latter has to bow or bend over. Moreover, the danger prevails that the resilient stiffeners penetrate the cover forming textiles of the corsets and girdles.

Corsets provided with spirally shaped springs are known, these springs being shaped into closed curves. Also these articles are unsatisfactory in use because an upsetting action is created at the reversal portions of the springs whereby the girdles are pierced and pressure and bruises created. If the sufficiently strong corset and girdle springs are used to meet these difficulties, the articles may exert an excessive and intolerable pressure.

It is the foremost object of the invention to eliminate the disadvantages of the hitherto customary elastic corset and girdle reinforcing members and inserts.

It is also an important object of the invention to attain a satisfactory shape stabilization of the corsets and girdles without a reduction of the rigidity of the elastic corset stiffening members.

With these and additional objects in view the invention will now be described more in detail and with reference to the accompanying drawing.

In the drawing:

Figs. 1 and 2 show plan views of the front portion of two modifications of a hip girdle made in conformity with the invention.

The drawing shows a slip girdle or corset consisting of a rubber fabric which preferably may be of the pull and push type. A front panel 2 which may be made of a satin fabric is sewed onto the girdle.

The panel 2 may be provided with a strong lining. A front shield 3 is fastened to the panel 2. This shield is provided with a pocket 10 fastened to the shield by seams 4; this pocket 10 harbours a spring 5; the individual spiral turns of this spring are pressure-flattened.

The shield 3 and the pocket 10 have the shape of a lyre consisting of a curved and closed inner end portion 6 and two lateral branches 11 of which one is substantially S-shaped and the second is oppositely S-shaped.

In this direction the instant lyre-shaped shield 3 differs essentially from the customary means of this type which are U-shaped or have the form of a horseshoe. As apparent from the drawing, the lateral branches 11 of the shown lyre-shaped front shield first approach each other and thereupon diverge from each other. The lyre-shape of the pocket and consequently of the spring 5 located

2

therein is clearly shown in the drawing. The distance between the two shanks of the spring 5 is smallest between the portions 7 thereof and largest at the ends 8.

If the female using this resilient corset or girdle has to move her back frequently and strongly, it is recommended to lengthen the shanks of the lyre-shaped spring 5 into circular end portion.

As further apparent from Fig. 1, a reinforcing member 9 is provided at the upper end of the lyre-shaped shield 3, which consists of a flat strip. This strip has a length which approximately equals the distance between the two free ends of the lyre-shaped spring 5.

This spring may be combined with plate-shaped reinforcing members of artificial materials or fabrics impregnated therewith.

As another type of additional reinforcing members a plurality of resilient flat rods may be applied to the inner space which is enclosed by the lyre-shaped reinforcing spring 5. These flat rods may extend vertically and may be located at a different distance from each other; they may also be disposed in a horizontal direction and combinations of vertical and horizontal flat rods or rod groups may be used.

The front panel 2' shown in Fig. 2 is slightly differently constructed than the front panel 2.

Its resilient shield 3' is lyre-shaped; however, the ends of the two branches extend inwardly. Moreover, the shield is located in such a manner that its upper rounded end portion substantially coincides with the upper rim of the panel 2'.

A plurality of these lyre-shaped resilient shields of a different size and shape may be concentrically disposed within each other; greater or smaller spaces may be provided between the same or they may be placed in a tight relationship to each other.

The lyre-shape of the resilient shield portion 3 represents the essence of the invention; it prevents the resilient rod-shaped inserts 5 located in the upper edge portion of the front panel from protruding from the same, tilting over or cutting into the girdle. The shape and the type of the resilient members 5 efficiently cooperate to impart to the waistline of the female body a good shape and to eliminate pressure spots.

The outwardly extending ends of the two shanks of the lyre-shaped resilient members take up those pressure components which are adapted to perforate the material of the front panel. On the other hand, the lyre-shape of the shield 3 enables a concentration of the resilient forces and a reinforcement of the same at the places where this action is mainly desired.

In dependence upon the directioning of the two lyre branches towards the upper edge, see Fig. 1, or the lower edge, see Fig. 2, of the front panel 2 the two shanks 5 of the lyre-shaped shield 3 approach each other in the upper or the lower third of the panel in a slightly curved direction. In this manner the resilient action of the shield portion 3 is increased within the range of its above noted portions without the creation of pressure spots.

Since certain changes may be made in the above article and different embodiments of the invention could be made without departing from the scope thereof, it is intended that all matter contained in the above description or shown in the accompanying drawing shall be interpreted as illustrative and not in a limiting sense.

Having thus described the invention, what I claim as new and desire to be secured by Letters Patent, is as follows:

In a corset having a front panel, a reinforcing member fixedly mounted in said panel, said reinforcing member

comprising a spiral spring of U-shape having upwardly extending curvular legs, said legs each being substantially centrally divided into an upper portion and a lower portion, both of said portions being concavo-convex in shape, said upper portions presenting their concave sides outwardly, and said lower portions presenting their convex sides outwardly, whereby said upper portions form upwardly and outwardly divergent arms. 5
